UNITED STATES PATENT OFFICE.

CHARLES EHRHARDT, OF CHICAGO, ILLINOIS.

DRINKING-FOUNTAIN AND SHOW-STAND.

SPECIFICATION forming part of Letters Patent No. 398,591, dated February 26, 1889.

Application filed July 24, 1888. Serial No. 230,903. (No model.)

To all whom it may concern:

Be it known that I, CHARLES EHRHARDT, a citizen of the United States, and a resident of Chicago, county of Cook, and State of Illinois, have invented new and useful Improvements in Drinking - Fountains and Show-Stands, of which the following is a specification, reference being had to the accompanying drawings, illustrating the invention, in which—

Figure 1 is a vertical central sectional elevation of my invention as constructed for use. The line of section is shown at W, Fig. 2; Fig. 2, a horizontal section of Fig. 1 on X, looking down.

This invention consists, in brief, of a substantial hollow post of iron or other suitable material, which is secured to the sidewalk or other desired place, where a suitable water-supply can be attained. In the top portion of this post is placed a cylinder which has a water-tight lower and upper head and a partition near the bottom head, with perforations near its periphery to permit water to escape near the cylinder, and the partition is provided with a step to support the lower end of a shaft which extends through and above the upper head. Affixed to this shaft inside of the said cylinder is a screw which is driven by the force of water coming from a supply-pipe entering the top portion of the cylinder and at its lower end connecting with a water-main. The water leaving the cylinder passes into a chamber below the partition and from thence through a faucet for supplying drinking-water. On the said shaft above the post is affixed a show-stand, to which is attached any bills, cards, or other advertising matter in the usual manner.

A represents the hollow post, which is attached to the sidewalk B at c c.

D represents a metal cylinder, which has tight heads F G, the head G being provided with a flange, by means of which and the screws a a it is secured to the post A. The

partition E is rigid in the cylinder D, and is provided with holes b b for the escape of water and a step, e, for the support of the shaft S. On this shaft is affixed a screw, I, and on the top of the head G is a stuffing-box, J, to prevent the escape of water, and to the upper portion of the shaft is affixed a show-stand, H, for the display of matter desired.

A suitable water-supply pipe, K, extends from the main into the hollow post A and from it by means of faucet L. A water-supply is furnished a trough, M, for animals to drink from, and a smaller pipe, N, taking water from pipe K, enters the upper portion of cylinder D and supplies water for turning the screw I and for drinking purposes through the faucet P. Below the latter faucet is the ordinary basin, R, and waste-pipe Q. The faucet L only takes a portion of the water from pipe K, whereby when open there is a supply of water for pipe N. From this it will be seen that when the faucet P is open the pressure of water in cylinder D will turn the screw I and consequently turn the show-stand H.

I intend to supply cities and villages with the devices shown, and that people shall be directed to the fountain by the rotation of the stands on the tops of the same.

I do not claim that there is a legitimate combination between a show-stand and drinking-fountain irrespective of construction.

Therefore, what I claim, and desire to secure by Letters Patent, is—

The hollow post A, the cylinder D G F, partition E, the post S, extending into and above the cylinder, the screw I within the cylinder and on the post S, and the show-stand H on the post above the cylinder, in combination with the water-supply pipes K N and faucet P, substantially as specified.

CHARLES EHRHARDT.
